[57] CLAIM

The ornamental design for a butterfly feeder, as shown and described.

DESCRIPTION

FIG. 1 is a top front perspective view of a butterfly feeder showing my new design;

FIG. 2 is a top plan view thereof;

FIG. 3 is a right side elevational view thereof; the left side elevational view being a mirror image;

FIG. 4 is a front elevational view thereof; the rear elevational view being a mirror image; and,

FIG. 5 is a bottom plan view thereof.

The broken line drawings of holes in FIG. 1 are for illustrative purposes only and form no part of the claimed design.
